UNITED STATES PATENT OFFICE.

RALPH S. PIPER, OF CHICAGO, ILLINOIS.

INDUCTIVE COUPLING DEVICE.

Application filed July 22, 1924. Serial No. 727,446.

My invention relates to improvements in variable inductance apparatus, such as commonly employed in wireless telegraphic and telephonic circuits. In this class of circuits much dependence is placed on the operation of the principle of resonance, as determinative of suitable working conditions of one circuit with respect to another. The application of this principle necessitates the use of variable condensers and variable inductance elements and my present invention is more especially concerned with the latter type of apparatus, sometimes called variometers, variocouplers, etc., according to the character of the connections between the inductance device itself and the circuits of which it forms a part.

In my Patent 1,438,854, granted to me Dec. 12, 1922, I disclosed and claimed a coupling transformer for use in radio circuits which utilizes windings presenting zones, or areas, of very close coupling characteristics alternating with other zones in which the coupling becomes progressively looser, and then progressively tighter. In this application I have extended the use of such a piece of apparatus, and analogous devices, by providing various regions of adjustability between windings that present areas of respective loose and close coupling characteristics. I will describe my invention more particularly in connection with the accompanying drawings, which constitute part of this specification, and in which—

Fig. 1 is a longitudinal section of a disc form of my invention.

Fig. 2 is an end elevation of the device shown in Fig. 1, with certain parts broken away.

Fig. 3 is a cross-section of a disk form of my invention.

In Figs. 1 and 2 I have shown a disc modification of the invention. In the disc form a shaft 16 carries a disc 8 securely mounted thereon by collars 74, this disc is made of some pliant non-conducting material and has a number of slots 14, as is usual in such parts in the art, through which a winding is threaded, as shown in Fig. 2. The shaft 16 also carries two sleeves 10, provided with flanges which support other discs 6 and 7, which are also of some resilient material and non-conducting, like hard rubber, these discs are also slotted like disc 8 to retain windings. Disc 6 may be a secondary to a primary on disc 8 and 7 may carry a tickler coil, or other

winding arrangements may be used, the invention is general in that respect.

The sleeves 10 are freely slideable, and rotatable on shaft 16, but may be fixed in any desired position of adjustment by set screws 11. These sleeves carry thimbles 9 freely slideable thereon which may also be locked in any position of adjustment by set screws. The thimbles 9 engage the hubs of conical reach members 5 which are beaded over the tops, or outer edges of discs 6 and 7. The relation of this beading being such with respect to the disc diameter that the parts may be easily sprung together. From the construction as described it will be seen that discs 6, 7 and 8 may be put into very close coupling relation throughout, if desired; furthermore discs 6 and 7 may be sprung away from disc 8 along their outer peripheries while their central areas are still closely coupled to disc 8. In the latter position of adjustment the outside discs 6 and 7 will bear against disc 8 somewhat as the back of a saucer, against a table. A further permissible adjustment would be to slack up set screws 11 after thimbles 9 had been adjusted to bend discs 6 and 7 and slide sleeves 10 to give any desired opening in the central areas also.

In the form of my invention shown in Fig. 3, 82 is a base plate of impregnated paper, bakelite, hard rubber etc. It carries a central bolt or shaft 85 moulded therein or otherwise fixedly secured thereto. Base plate 82 also carries a hub 88 integral therewith and an integral peripheral bead 89. The latter is used to act as the rest or support of the periphery of a star shaped coil structure 90, which is made up of a central disc portion and a number of sectors or arms, as in the usual card board spider-web support. I have shown two of these arms 81 and 87 resting on the bead 89, the center of the disc 90, or other concavo-convex coil 90, surrounds the hub 88 of the base plate 82, and is surmounted by a true disc coil 80, which also is concentric with hub 88. The coil 90 is given a permanent initial set so that it is always convex upwards when resting on bead 89 and not under pressure due to the action of a thumb nut 84 and collar 83. The function of these latter being to compress the two coils 90 and 80 together, when this pressure is removed the resilience of coil 90, assisted by spring 86 returns the system to an open-coupled relation of the two discs, as shown in Fig. 3.

The operation of this form of the invention

will be understood from the above detailed description of parts. The central portion of disc 90 remains constantly in close coupling with top disc 80, but as nut 84 is turned to 5 clamp the two discs together, the gap between them becomes less and less; however, if desired a packing washer 92 may readily be inserted between the central portions of the two discs, by running off nut 84 and lifting 10 the top disc 80 off the bolt 85. As shown in Fig. 3, the contact of the two discs is similar to that which exists between a saucer and a table on which it rests. As the winding passes from one arm to the next of disc 90 a small 15 allowance of free wire is needed to allow for spreading of these arms when flattened against the other coil.

One reason that the above described devices appear to produce especially favorable 20 results in oscillatory circuit adjustments probably depends on the well known fact that all such circuits require a certain amount of capacity and a certain amount of inductance, depending in amount on the particular circuit. If precisely the right amount of both 25 capacity and inductance could be inserted in the circuit at the first adjustment, evidently the circuit would immediately drop into step with the reactions of the circuits with 30 which it co-operates. In the prior art this right amount has always been determined by a series of approximations which involve

varying the whole amount of the inductance in circuit, but it will be found as a characteristic of the devices described above that they 35 make the necessary adjustment on only a fractional part of the whole amount needed. For many circuits it will be known that at least a given amount of inductance will be needed and that much can be left in circuit without 40 change, thus contributing to the stability of the adjustment. It is a well known property of all kinds of resonant agreement that the nearer conditions are to perfect agreement 45 the easier it is to bring them into complete accord.

What I claim as my invention is:

1. A radio coupling transformer, comprising a plane faced element, a winding supported thereby and a convex faced element, 50 a winding carried thereby and opposed to said plane faced element.

2. A radio coupler transformer comprising a concavo-convex coil, a plane disc coil in combination therewith, and means for varying the spacing around the edges of said coils. 55

3. A radio coupler assemblage comprising two radially wound coils of general disk contour and means for keeping their central portions a fixed distance apart and for varying 60 the distance apart of their peripheral portions.

RALPH S. PIPER.
